UNITED STATES PATENT OFFICE

145,107

DESIGN FOR A JACKET FOR BOILER OR FURNACE

Peter Schladermundt, Bronxville, N. Y., assignor
to Sears, Roebuck and Co., Chicago, Ill., a cor-
poration of New York

Application August 27, 1945, Serial No. 121,660

Term of patent 7 years

(Cl. D81—2)

To all whom it may concern:

Be it known that I, Peter Schladermundt, a citizen of the United States, and a resident of Bronxville, in the county of Westchester and State of New York, have invented a new, original, and ornamental Design for a Jacket for Boiler or Furnace, of which the following is a specification, reference being had to the accompanying drawing, forming a part thereof.

Fig. 1 is a front perspective view of a jacket for boilers or furnaces, embodying my new design.

Fig. 2 is a side elevation thereof, and
Fig. 3 is a plan view thereof.

The sides of the jacket, not shown, are substantially plain.

I claim:

The ornamental design for a jacket for boiler or furnace, substantially as shown and described.

PETER SCHLADERMUNDT.
